[57] ABSTRACT

This disclosure relates to an expandable metal belt which is made expandable by springs held within adjacent tubular links.

FIG. - 1

FIG. - 2

FIG. - 3

FIG. - 5

FIG. - 6

FIG. - 7

EXPANDABLE BELT

BACKGROUND OF THE INVENTION

Various methods have been in existence to create an expandable belt or band for belts and/or watches.

These methods have required complex tooling which results in an expensive product.

It is an object of the present invention to provide a new and inexpensive expandable metal belt or band.

It is a further object of this invention to provide an expandable metal belt or band which is simple to manufacture and assemble and is adjustable to any size.

Still a further object of the invention is to provide an expandable metal belt or band which requires no tooling and is composed of standard replaceable parts.

These and other objects will be obvious from the following description and drawings in which:

FIG. I is an exploded view of one link of the present invention

FIG. II is a side elevation view partially broken away of two adjacent links of the present invention

FIG. III is a side elevation view of two links of the present invention in an expanded position

FIG. IV is a side elevation view partially broken away of another embodiment of the present invention

FIG. V is the embodiment of FIG. IV in an expanded position

FIG. VI is a side elevation view, partially broken away of another embodiment of the present invention

FIG. VII is the embodiment of FIG. VI in an expanded position

Referring now to FIG. I, there is shown one link of a belt comprising two pieces of tubing 10, 12 which are threaded internally at both ends, only one end is shown 14, 16. A spring 18, 20 fits inside of tubing 10, 12.

An eyelet 22, 24 fits through the end of spring 18, 20 and fixedly attaches to a chain such as a snake chain 26 whose ends pass through springs 18, 20 and attach to eyelets 22, 24.

Snake chain 26 passes through a hole in collars 28, 30. Collars 28, 30 are threaded externally to threadably attach to threaded ends 14, 16 of tubes 10, 12. Other methods of attaching the collars to the tubing may be utilized such as welding, however, threading is preferred due to ease of construction and repair.

The collars 28, 30 and eyelets 22, 24 hold springs 18, 20 inside of tubes 10, 12. When a pulling force is exerted on snake chain 26, as when the link is expanded, collars 28, 30 prevent the springs 18, 20 from coming out of tubes 10, 12 and eyelets 22, 24 attached to snake chain 26 press against springs 18, 20 compressing them.

A double tube connector 32 connects two adjacent links by snake chain 26 passing through one tube of the double tube connector 32.

FIG. II shows two complete adjacent links fitted together with the tubing of the right link 34, 36 in which the springs 38, 40 are contained by collars 42, 44 which are threadably connected to tubing 34, 36. Eyelets 46, 48 are fixedly attached to the ends of snake chain 50.

Snake chain 50 passes thru one side of double tube connector 52.

The left link also comprises tubing 54, 56 containing springs 58, 60 held by collars 62, 64. Eyelets 66, 68 are fixedly attached to snake chain 70 which passes through the other side of double tube connector 52.

It can be seen that in operation pulling or expansion of the links shown will cause the tubing 34, 36 and 54, 56 to be pulled in opposite directions pulling snake chains 50, 70 out of tubes 34, 36, 54, 56, compressing springs 38, 40 and 58, 60 thus providing an expandable belt as each successive link is expanded.

There is shown adjacent double tubing connectors 72, 74 which connects the next link in the belt.

FIG. III shows two adjacent links in an expanded state with tubing 76, 78, 80, 82 having collars 84, 86, 88, 90, 92, 94, 96 and 98 threadably attached in each end of the tubing. Snake chains 100, 102, 104 & 106 pass through tubing 76, 78, 80 & 82 and are held inside by eyelets as shown in FIG. II. Double tube connectors 108, 110 & 112 connect four consecutive links of the belt together. Pulling the ends of the links as shown would cause expansion of the belt by pulling snake chains 100, 102, 104 & 106 out of tubing 76, 78, 80 & 82 compressing the springs inside. Upon release the springs would bring the belt back to its unexpanded state.

Referring now to FIG. 4 and 5 there is shown another embodiment of the invention using the spring principle but with a different method of assembly and connection.

The links consist of a U-shaped tubing 114, 116 with connectors 118, 120 connecting adjacent U-shaped tubes together. Springs 122, 124 are held in U-shaped tube 114 by collars 126, 128 threadably attached to the ends of U-shaped tube 114. Eyelets 130, 132 are fixedly attached to the ends of snake chain 134 which passes through the collars 126, 128 and double tube connector 136. Similarly snake chain 138 passes through the other side of double tube connector 136 and is held in the next adjacent link.

FIG. V shows the links in an expanded state where expansion of the links pulls the snake chains 134, 138 out of tubes 114, 116 causing expansion of the belt.

FIG. VI and FIG. VII show another embodiment using the same principle in which adjacent links comprise U-shaped tubes 140, 142, 144 & 146. The tubes are connected on one end by clip connectors 148, 150, 152. The tubes are connected and expansion provided by springs 154, 156 held in tubes 140 & 142 and similarly 144 & 146 (not shown). Collars 158, 160 are threadably attached to U-shaped tubes 140 & 142. Eyelets 162, 164 are fixedly attached to the ends of snake chain 166.

FIG. VII shows expansion of the links where the U-shaped tubes are pulled apart exposing snake chains 166 and 168 compressing the springs in the U-shaped tubes.

The tubing may be in any desirable shape and may be made of any desired material such as aluminum. The belt may be sized by adding or deleting links and if made on a smaller scale can be used as a bracelet or watch-band.

Should any portion of the belt or band break, such as a chain or eyelet, they can be easily replaced by using no more than a standard hand-pliers to remove the collars and replace the broken part.

The belts or bands may be made of aluminum that has been treated to give it an attractive color or other metals that are pleasing in looks or even plastic or other materials adaptable for this use.

Having thus described the invention it is desired that the invention be limited only by the scope of the appended claims.

I claim:

1. An expandable belt comprising a plurality of tubing, a collar adapted to attach to said tubing, a chain passing through a hole in the collar, a spring in said tubing held by an eyelet attached to the end of the chain, a connector adapted to receive said chain, and said tubing is threaded internally and said collar is threaded externally.

2. The belt of claim 1 in which the tubing is U-shaped.

3. An expandable belt comprising a plurality of pieces of tubing threaded internally at the ends, collars threaded externally to attach to said tubing, springs adapted to fit inside said tubing, chains adapted to fit through said tubing and collars, and eyelets affixed to the ends of the chains.

4. The belt of claims 3 in which double tube connectors attach adjacent chains together.

5. An expandable belt comprising a plurality of links

each link comprising two pieces of tubing threaded internally at each end, collars threaded externally to attach to said tubing, springs adapted to fit into each end of the tubing, chains adapted to fit through said collars and tubing, eyelets attached to the ends of said chains adapted to attach the ends of the chain to the ends of the springs.

6. An expandable belt comprising a plurality of links each link comprising a U-shaped tube threaded internally at the ends, collars threaded externally to attach to said tube, springs adapted to fit in the ends of said tube, a chain adapted to fit into each end of the tube, eyelets attached to the ends of the chain adapted to attach the ends of the chain to the ends of the springs.

7. The belt of claim 6 wherein adjacent links are connected by double tube connectors.

8. The belt of claim 6 wherein adjacent links are connected by clips.

9. The belt of claim 6 wherein the chain is a snake chain.
